UNITED STATES PATENT OFFICE.

ALEXANDER JACKSON FIKE AND CHARLES MORGAN FIKE, OF CLIFTON MILLS,
WEST VIRGINIA.

TABLE.

No. 902,955.

Specification of Letters Patent.

Patented Nov. 3, 1908.

Application filed April 20, 1908. Serial No. 428,067.

To all whom it may concern:

Be it known that we, ALEXANDER JACKSON FIKE and CHARLES MORGAN FIKE, citizens of the United States of America, residing at 5 Clifton Mills, in the county of Preston and State of West Virginia, have invented certain new and useful Improvements in Tables, of which the following is a specification, reference being had therein to the accompanying drawing.

This invention relates to tables, and the objects of our invention are, first, to provide a table with a revoluble support for dishes, whereby persons seated at the table can conveniently wait upon themselves; second, to provide a table wherein novel means are employed for moving dishes about a table; third, to obviate the necessity of passing dishes from one person to another seated at 20 a table; fourth, to provide a table with superimposed revoluble supports and a stationary support for a lamp, candelabrum or vase; fifth, to provide a table with a revoluble dish support which can be easily and 25 quickly removed when the table is to be used for other purposes, and sixth, to provide a table having revoluble platforms that can be located in a stationary position.

We attain the above objects by the construction which will be presently described 30 in detail and then specifically pointed out in the appended claims.

Referring to the drawings forming a part of this specification, Figure 1 is an elevation 35 of our table partly broken away and partly in section, Fig. 2 is a plan of a drawer section of our table, Fig. 3 is an elevation of our table partly in section, illustrating a 40 arrangement of the parts thereof, and Fig. 4 is a plan of the same.

To put our invention into practice, we provide a base, a revoluble drawer section, a revoluble table top, and revoluble superimposed platforms which are so arranged 45 that the table top can be dispensed with if desired.

The base of the table comprises suitable legs or supports 1 connected to a central standard 2, having therein a vertical stationary 50 post 3.

The drawer section of our table comprises a bearing plate 4, and brackets 5 connected by a central standard 6, said standard receiving the upper end of the post 3. The brackets 5 support an annulus or ring 7 provided with a plurality of circumferentially arranged roller bearings 8. The annulus or ring 7 is formed with radially disposed openings 9 for drawers 10.

The standard 6 extends above the annulus or ring 7, and is provided with a central rod 11 having its upper end provided with an interiorly threaded socket 12.

The drawer section of our table is adapted to revolve upon the base of the table, and to 65 lock the same in a stationary position, we provide one of the legs or supports of the table with a pivot lever 13 having a locking rod 14 adapted to extend upwardly through the flange 15 of the block 2 and engage in 70 the bearing plate 4 of the drawer section.

Revolubly mounted upon the roller bearings 8 of the drawer section is a table top 16, said table top having a central opening 17 to accommodate the upper end of the standard 6. The under side of this table top is provided with radially disposed guideways 18 for drawers 19, these drawers being located at the periphery of the table top.

To lock the table top stationary with respect to the drawer section of the table, we provide one of the brackets 5 with a pivot lever 20 having an upwardly extending locking pin 21 extending through the annulus or ring 7 to engage in the table top 80 16, as clearly shown in Fig. 1 of the drawings.

Mounted upon the rod 11 is a bearing plate 22 having a bearing block 23, said bearing plate and said bearing block supporting the superimposed platforms of our 90 table.

The main platform 24 is recessed, as at 25, to receive the block 23, and is provided with a central column 26 apertured to receive the 95 rod 11 and supporting a revoluble platform 27. The column 26 is made in two parts, whereby the platform 27 can be revolubly mounted upon the reduced upper end of the lower part of the column, the upper part 100

of the column being connected to the lower part by dowel pins 28 or similar fastening means.

Adapted to screw into the socket 12 of the rod 11 is a depending threaded pin 29 of a platform 30, this platform being designed to support a lamp 31 or a candelabrum, or similar center piece. The platforms 24 and 27 have their edges provided with 10 equally spaced knobs or buttons 32, serving as handles for rotating the platform.

In Fig. 3 of the drawings, we have illustrated the table top 16, bearing plate 22, and bearing block 23 as being dispensed with, 15 and superimposed platforms mounted directly upon the drawer section of our table. The locking pin 21 of the drawer section can also be employed for locking the main platform 24, and in this connection we would 20 have it understood that the under sides of the table top 16 and the main platform 24 are provided with a plurality of openings for the locking pin 21, whereby the table top 16 or the platform can be easily made stationary 25 with respect to the drawer section of our table.

The bearing plate 4 between the brackets 5 serves functionally as a shelf, and the drawers 10 and 19 can be used for numerous purposes.

We preferably make our table of a circular form, and it is obvious that for banquet purposes the table can be beautifully decorated and a large number of guests 35 easily served. When the table is not being used for dining purposes, the table top 16 is removed, and then the table can be used as a sewing table or for any desired purposes.

40 With the superimposed platforms removed, and the platform 30 mounted upon the standard 6, the table can be used for cards or similar games, a lamp being located upon the platform 30 to illuminate the 45 entire surface of the table.

We reserve the right to make our table octagon, hexagon or any desired shape, and such other changes in the details of construction as are permissible by the appended 50 claims can be resorted to without departing from the scope of the invention.

Having now described our invention what we claim as new, is:—

1. A table embodying a base, a post carried thereby, a drawer section revolvably mounted upon said base, said drawer section comprising brackets, a central standard, an annulus supported by said brackets, drawers slidably mounted in said annulus, roller 55 bearings carried by said annulus, a central rod carried by said standard, a table top revolvably mounted upon said roller bearings, drawers slidably mounted upon the under side of said table top, superimposed revo-

luble platforms surrounding said rod above 65 said table top, a detachable platform mounted upon the upper end of said rod, means carried by the base of said table for holding said drawer section stationary, and means carried by one of the brackets of said drawer 70 section for holding said table top stationary.

2. A table embodying a base, a post carried thereby, a revolvble drawer section mounted upon said post, said section comprising a vertical standard, an annulus, and roller 75 bearings; a table top revolvably mounted upon said roller bearings, revolvble superimposed platforms surrounding said standard above said table top, a platform carried by the upper end of said standard, means projecting 80 through said annulus to hold said table top stationary, and means carried by said base for holding said drawer section stationary.

3. A table embodying a base, a drawer section revolvably mounted thereon, said section 85 comprising a central standard, an annulus, and drawers; a table top revolvably mounted upon said annulus, drawers carried thereby, superimposed revolvble platforms surrounding said standard above said table top, means 90 projecting through said annulus for holding said table top stationary, and means carried by said base for holding said drawer section stationary.

4. A table embodying a base, a drawer section revolvably mounted thereon, said section comprising a central standard, an annulus, and drawers; a table top revolvably mounted upon said annulus, superimposed revolvble platforms surrounding said standard above 100 said table top, means projecting through said annulus for holding said table top stationary, and means carried by said base for holding said drawer section stationary.

5. A table embodying a base, a revolvble 105 drawer section carried thereby, said drawer section comprising an annulus, drawers, and a central standard; a table top revolvably mounted upon said annulus, revolvble superimposed platforms surrounding said standard above 110 said table top, means carried by said base for holding said drawer section stationary, and means carried by said drawer section for holding said table top stationary.

6. In a table of the type described, a base, 115 a revolvble section carried thereby and embodying an annulus and a central support, a table top revolvably mounted on said annulus, a two-part column mounted on the upper end of said central support, platforms carried by said column, means for securing the table top in fixed position, and means for locking the revolvble section against rotation.

7. A table of the type described comprising 125 a supporting base, a revolvble section mounted on said base, a table top mounted on the revolvble section and rotatable thereon inde-

pendently of said section, a column supported from said rotatable section above the table top and provided with a plurality of superimposed platforms rotatable with the column 5 independently of the table top, means for securing said base section against rotation, and means for holding the table top in a fixed position.

In testimony whereof we affix our signatures in the presence of two witnesses.
